DOOR HANDLE

Fred Brown, Sylvania, Ohio, assignor to Doehler
Die Casting Co., Toledo, Ohio, a corporation
of Ohio

Application July 11, 1938, Serial No. 218,604

9 Claims. (Cl. 292—348)

This invention relates to improvements in door handles.

The main objects of my invention are:

First, to provide a novel mounting for a handle 5 for operating a window operator, door latch, or the like.

Second, to provide a novel means for attaching an operating handle to an operating spindle or chill which permits ready assembly and dismantling of the parts.

Third, to provide a handle mounting of the type described characterized by its simplicity and economy of production.

Fourth, to provide a handle assembly which is 15 proof against accidental displacement.

Further objects relating to details and economies of my invention will definitely appear from the description to follow. The invention is defined in the claims.

20 A structure embodying the features of my invention is illustrated in the accompanying drawing, wherein:

Fig. 1 is a fragmentary side view illustrating a door with a handle embodying my invention 25 mounted thereon.

Fig. 2 is a fragmentary view in section on line 2—2 of Fig. 1, illustrating the parts of my assembly in operative position.

Fig. 3 is a view similar to Fig. 2, being in section on line 3—3 of Fig. 4, illustrating the manner in which the parts of the mounting are assembled.

Fig. 4 is a fragmentary detail view illustrating the handle of my invention.

35 Fig. 5 is a view in section on line 5—5 of Fig. 2, further illustrating the construction.

Referring to the drawing, the reference numeral 1 indicates an automobile door or other part whereon it is desired to assemble a handle 40 mounting for operating a latch mechanism, window elevating mechanism, or other manually actuated part. The reference numeral 2 in general indicates the handle assembly or mounting 45 and the reference numeral 3 designates an inner upholstered flexible panel such as is ordinarily found on automobile doors.

The door 1 is provided with a bracket or guide member 4 on the interior thereof for guiding the 50 rotatable spindle or chill 5 forming a part of a latch or other instrumentality (not shown) which it is desired to rotatably actuate. This spindle or chill is square in section and is surrounded by a coil compression spring 6 bearing against 55 the inner side of panel 3 and the guide 4 with a

thrust washer or shim 7 interposed between the guide and spring.

The panel 3 is apertured at 8 to receive the free end 9 of the chill and to likewise receive a sliding retaining collar or thimble 10 which has a square central aperture slidably fitting on the chill. In the embodiment illustrated the collar or thimble is shouldered at 11 and is peened or hammered at 12 and annularly flanged at 13 to prevent separation thereof from an escutcheon 10 member 14 with which it is associated. The peening, however, is merely a matter of retaining the parts in assembled relation for convenience in handling, and is unnecessary so far as functioning of the parts is concerned. From the foregoing disclosure it is seen that the escutcheon member and collar 10 are depressible axially of the chill 5 for a purpose to be described.

The end 9 of the chill is milled or ground to provide an angular or oblique tongue 15 disposed at an angle of approximately 15 degrees to the axis of the chill. The handle, indicated by the reference numeral 16, has a flat circular bearing abutment 17 adapted for thrust engagement with the escutcheon member 14 and 20 the flange 13 of the collar in assembled position, as illustrated in Fig. 2. Within this annular abutment there is a circular upstanding boss-like shank 18 of approximately the same diameter as the interior diameter of the collar and 25 adapted to be slidably and telescopingly engaged thereby during assembly of the structure and in assembled position. The shank 18 is provided with a diagonally arranged recess conforming in cross sectional area to the cross sectional area 30 of tongue 15 and adapted to engage the said tongue to rotate chill 5.

From the foregoing description it is evident that the handle 16 may be assembled on the chill only by a combined lateral and axial movement 40 relative to the chill, this being due to the angular inclination of the tongue 15 and recess 19. However, it is equally evident that the shank 18 and the retaining collar may not be operatively engaged by anything other than a purely axial 45 relative sliding or telescoping movement. Therefore, in assembling the structure the escutcheon 14 is depressed, carrying the collar 10 to a point below the tongue 15 of the chill, as illustrated in Fig. 3. The recess 19 of the handle is thereupon 50 slidably engaged with the tongue in the direction indicated by the arrow in Fig. 3. This movement brings boss 18 and collar 10 into coaxial relation, whereupon release of the escutcheon permits the collar to be pushed outwardly by 55

spring 6 into telescoping and retaining engagement with the boss. In such position removal of the handle 16, either in an axial or a lateral direction, is obviously impossible, and the parts 5 are held very firmly by the spring 6 in this relation.

The simplicity of the parts, as well as the ease of assembly and effectiveness thereof, recommends the above described structure. It is proof 10 against accidental displacement and possesses all the strength that a manually operated mechanism of the type under consideration requires.

I have illustrated and described my improvements in an embodiment which is very practical. 15 I have not attempted to illustrate or describe other embodiments or adaptations as it is believed this disclosure will enable those skilled in the art to embody or adapt my improvements as may be desired.

20 Having thus described my invention what I claim, as new and desire to secure by Letters Patent is:

1. A handle assembly for a door comprising an operating spindle extending through a panel 25 in a door, a collar in axially slidable engagement with said spindle, said collar providing an annular recess surrounding the spindle, a coil spring surrounding the spindle and serving to urge the panel and collar outwardly, said spindle terminating in a tongue disposed angularly relative to the axis of the spindle, and a handle having a shank conforming in cross section with said annular recess and adapted to fit telescopingly therein, said shank having a recess therein disposed at an angle to the axis of the shank similar to the angular disposition of the tongue and engageable with said tongue to rotate the spindle, said collar being movable axially of the spindle against the force of said spring to permit engagement of the tongue and shank recess in a direction oblique to the spindle axis to effect alinement of the shank with the collar recess, release of the collar thereafter resulting in telescoping engagement of the shank and collar due to the expansive action of the spring. 45

2. A handle assembly for a door latching or equivalent device comprising a spindle operatively connected to the device, a collar in axially slidable engagement with said spindle laterally fixed in relation thereto, said spindle terminating in a tongue disposed angularly relative to the axis of the spindle, and a handle provided with a shank, said shank having a recess therein disposed at an angle to the shank and engageable with said tongue to rotate the spindle, said collar telescopingly engaging said shank in operative position to prevent separation of the tongue and handle and being shiftable axially of the spindle to clear the shank and permit engagement or disengagement of the tongue and shank recess. 60

3. In combination, a rotatable operating handle for a door having an inner flexible panel, and a handle assembly for actuating said spindle comprising a collar slidably engaging the spindle, a handle member having a shank telescopingly engageable with said collar in operative position of the assembly, and an extension on the end of said spindle disposed at an angle 70 of approximately 15 degrees to the axis of the spindle, said shank being provided with a correspondingly angled recess conforming in outline to the cross section of the extension and adapted to slidingly engage the extension to bring the shank and collar in coaxial alinement, 75

and means for engaging the panel and collar for depressing the latter to permit engagement and disengagement of the handle with the extension, said boss telescopingly engaging within the collar upon return of the collar to original 5 position whereby displacement of the handle is prevented.

4. In combination, a rotatable operating spindle for a door, and a handle assembly for actuating said spindle comprising a collar slidably engaging the spindle, a handle member having a portion telescopingly engageable with said collar coaxially of the spindle in operative position of the assembly, an extension on the end of said spindle disposed at an oblique angle to the axis of the spindle, said handle being provided with a correspondingly angled recess adapted to slidingly engage the extension, and means for urging said collar in a direction for telescoping engagement with said portion to prevent disengagement of said tongue and recess. 20

5. In combination, a rotatable spindle, a handle for actuating the spindle, and means for operatively connecting said handle and spindle comprising a collar surrounding and slidably engaging the spindle, said handle having a portion telescopingly engageable with said collar by axial relative movement of the collar and portion, said spindle and handle having means for telescoping engagement and disengagement by 30 a combined axial and other than axial movement, said collar in operative telescoped position relative to said handle portion preventing said combined movement, and means for urging said collar outwardly to said operative position, said last-named means being depressible to permit telescoping engagement of said handle and spindle prior to telescoping engagement of said collar and handle portion. 35

6. In combination, a rotatable spindle, a handle for actuating the spindle, and means for operatively connecting said handle and spindle comprising a retaining collar surrounding and slidably engaging the spindle, said handle having a portion telescopingly engageable with said collar by 40 axial relative movement of the collar and portion, said spindle and handle having means for engagement and disengagement by relative telescoping movement in a direction at an angle less than 90 degrees to the axis of the spindle, 45 said retaining collar preventing said angular movement when in operative telescoped position, and means for maintaining said collar in operative position. 50

7. A handle assembly of the type described comprising a rotatable spindle, a handle engageable with said spindle, an element slidably axially of and non-rotatable on said spindle, means for resiliently urging said element in an axial direction, said handle having a portion telescopingly engageable with and disengageable from said spindle by a relative movement including an axial component and a lateral component, said element being urged axially by said resilient means to a position wherein it prevents said relative movement of the spindle and said portion. 55

8. A handle assembly of the type described comprising a handle, a rotatable spindle actuated thereby, an element slidably axially of said spindle, and means for maintaining said element in 70 predetermined operative position axially of the spindle, said handle having a portion telescopingly engageable with and disengageable from said spindle by a compound movement including a lateral component, said element in operative 75

position preventing said compound movement of said portion and spindle and being displaceable from operative position to permit said movement.

5. A handle assembly of the type described comprising a handle, a rotatable spindle actuated thereby, an element on said spindle, and means for maintaining said element in a predetermined operative position axially of the spin-

dle, said handle having a portion disengageable from said spindle by a compound movement including a lateral component, said element in operative position preventing said compound movement of said portion and spindle and being displaceable from operative position to permit said movement.
